UNITED STATES PATENT OFFICE

HEINRICH WALTHER, OF FRANKFORT-ON-THE-MAIN-OBERRAD, GERMANY

VULCANIZING PRESS

Application filed February 24, 1932, Serial No. 594,829, and in Germany September 23, 1931.

Hitherto very expensive machines and a very careful working was needed for the application of rubber soles. For every size of shoe and every form many metallic sole forms adapted to be heated and a corresponding number of metallic lasts were indispensable if a reasonable amount of work had to be done. For effecting the vulcanization the sole forms had to be held in contact with the lasted shoes under a considerable pressure and at a certain precise temperature for half an hour.

According to another method of manufacturing shoes with rubber soles applied by vulcanization metallic sole forms not adapted to be heated and the metallic lasts with the shoes thereon are at first pressed against each other and are then deposited in bulk in big heating drums wherein they are brought to the desired temperature and are left for a certain time.

It is evident that already the production of the forms for the soles and the lasts entails enormous expenses in view of the fact that for every size, every width and every shape of the shoe for right and left shoes a separate sole and last form is necessary. Moreover the means for heating the forms and the lasts is very expensive.

The present invention has for its object a vulcanizing press which may be obtained for a relatively small price and which gives a great output and is simple to operate. To small and middle factories is therefore afforded the opportunity to manufacture shoes with soles applied by vulcanization without investing considerable sums for the machines.

In the drawing an embodiment of the invention is shown.

Fig. 1 illustrates the general construction of the machine in an elevation and partly in an axial section.

Fig. 2 shows a part of the machine in a front view, partly in a cross section.

Fig. 3 shows a longitudinal section of the front part of the shaft and of the steam distributor.

Fig. 4 is a front view of the inlet and outlet of the steam and of the valves.

Figs. 5 and 6 are schematical views of the steam distributor in a cross section on the lines A—B and C—D of Fig. 3.

Fig. 7 shows a detail.

In the fixed standards 1 and 2 is journaled the shaft 3 (Fig. 1). On the shaft 3 is fastened the circular carrier 4 to which are screwed the front and the rear brackets 5 and 6 which carry at 7 and 8 the pressing devices. Every pressing device consists of a pressing pan 9 encircled by the insulating pan 10 the free space of which is filled with a material 11 insulating the heat. To the pressing pan 9 is fastened by screwing a tightening ring 13 a press cover 12 of a flexible material. The insulating pan 10 is likewise fastened to the press pan 9. This all forms the pressing device or pressing cushion. Only the arrangement described the pressing device has a pressing chamber 14 wherein a pressure may be created by steam or a heating gas supplied by the pipe joints 15, 16. The heat insulating material 11 is inserted into the pressing devices in a manner as a propagation of the heat through the cover 12 in contact with the work piece is fully obtained while the undesirable radiation in other directions is obviated. Further the pressure devices are inclined so that the condensate may drain through the joint 16. The inclination is directed against the face of the attendant so that he may easily work and have a good sight.

The heat and pressure medium as steam, gas, water is supplied by means of a distributor. The distributor consists of the outer body 30 rotating with the shaft 3 and with the carrier 4 and which is connected with the pressing devices through the inlet pipes 17 and the outlet pipes 18. The distributor consists further of the parts 19, 24 connected to each other and the standard 1. The distributor has to control the passage of the heat and pressure medium coming from a producer and to free or partly or wholly close the passage according to the requirements and to distribute the medium to the single pressing devices. To this end the front part 19 has three chambers *a*, *b*, *c*. The chamber *a* may be denominated as the

fresh gas chamber and is by means of the interposed cut-off valve 20 and the reducing valve 21 provided with the manometer 39 in direct communication with the producer of the pressure and heat medium. It communicates through the longitudinal channel a' with the ring channel a'' of the part 24. The chamber c communicates through the longitudinal channel c' with the ring channel c'' of the part 24 and with the safety valve 23. The chamber b is for the exhaust gases and it leads to the exhaust pipes 22. The chamber c with the adjustable valve 23 for the superpressure serves as a superpressure chamber. The front part 19 is tightly connected to the ringlike inner member 24 having the channels a' , b' , c' by the screws 26. Between the member 24 and the journal ring 25 is inserted a heat insulating disc 27. The parts 25, 24 and 19 form a rigid unit screwed with seating faces of the front part 19 to the standard 1.

On the ringlike inner member 24 rotates together with the inlet bores 28 and the outlet bores 29 the ringlike outer member 30 by being connected through the coupling bolts 32 and the brackets 31 to the rotating carrier 4. Each bore 28 is connected to the pressing device by the pipe 17 and each bore 29 is connected thereto by the pipe 19. The bores 28 communicate with the ring channel a'' and allow by these means the fresh steam to pass from the chamber a into the pressure chambers 14 of the pressing devices. Out of the bores 29 only one can communicate at a time with the longitudinal channel b' and the exhaust chamber b . The live steam is admitted through the ring channel a'' to all pressing devices except the one device the admission bore 28 of which is just closed by the cut-off cam 42 of the member 24, as shown in Fig. 6. While the admission to this pressing device is cut-off its exhaust bore 29 is in communication with the channel b' and the exhaust-chamber b , as illustrated in Fig. 5. Most of the other exhaust bores 29 remain in communication with the ring-channel c'' . If an exceeding pressure is introduced or if it is created by the pressing process, then the safety valve 23 of the ring-channel c'' is opened and the pressure medium finds its way into the atmosphere. The valve 23 is so adjusted that a small quantity of the steam is perpetually being exhausted so that fresh steam can be introduced. Fig. 5 shows that the channel b' is so shaped that in rotating in a clockwise direction it registers not only with the uppermost bore 29 but also with the next following one. By these means the heating gas can be freely blown through the pressing device onto which the work-piece has been just placed in order to remove the cold residues of the gas from this device.

63 The packing rings 33 on both sides of the

body 30 are pressed by the nuts 35 against the packing material 34 and assure the necessary tightness. The nuts 35 are crosswise provided with holes so that they may be tightened by a bolt introduced in a hole. 70

The machine is attended to and is operated as follows:

A work-piece (a shoe) to be vulcanized is placed upright by hand upon a pressing device of the machine, preferably upon the uppermost one. Then the slide 47 with the roll 53 is moved upwards by the slide 57 by means of a handle or a treadle. Whereby the adjusting screw 52 abuts against the dog 51 of the pressing lever 38 journaled on the pivot 55 of the bracket 6 so that the stirrup 37 and its pressing feet 36, 43 are swung against the work-piece. The slide 47 is held in this position by the toothed lever 49 which is acted upon by a spring. The treadle or handle can now be released. In this manner shoes are introduced into all pressing devices whereupon the pressing devices are put under pressure. This is done by opening the shut-off valve 20. The heating pressure medium flows at first through the pressure reducing valve 21 which is adjusted for the necessary working pressure and automatically prevents the pressure to exceed the allowed limit. At the same time a manometer 39 arranged on the reducing valve indicates the height of the pressure. The heating pressure medium enters the chamber a flows through the channel a' and comes into the ringlike distributing channel a'' (Fig. 6). The branch holes 28 arranged in the circumference of the outer ring 30 are in communication with the distributing channel a'' . The pressure medium can now pass through the holes 28 and the ducts 17 into the pressure chambers 14. The cover 12 is now pressed against the work-piece, it presses the sole on and effects by the heat of the pressure medium the vulcanization. Through the ducts 18 and the holes 29 of the outer ring 30, Fig. 5, the pressure rooms 14 communicate with the ringlike superpressure channel c'' and through the longitudinal channel c' they communicate with the chamber c of the part 19. The reducing valve 23 of the chamber c is so adjusted that a small quantity of the pressure medium is constantly escaping, so that fresh hot pressure medium flows through the pressing devices. By these means the pressing devices are constantly heated with fresh steam and the condensation of the pressure medium within the machine is almost wholly prevented. At any time the uppermost hole 29 of the outer distributor communicates with the outlet channel b' which itself communicates with the outlet chamber b of the part 19, by the arrangement of the closing cam 42 and of the outlet hole b' , it is obtained that the pressing device occupying the uppermost 100

middle position is out of the pressure-region. The machine is automatically and successively rotated in any well known manner and comes to rest after every partial rotation in order to allow the removal and the introduction of the work-piece. When the machine is rotating the roll 53 comes to ride over the cam-disc 58 fastened to the frame 2, so that the pressing members on all shoes have the same position. Further it is thereby prevented that these members hang down in their lower position in the case the attendant omits to operate the handle or the treadle. The shaft 1 is rotated every time for one pressing device so that all devices are successively freed from pressure. As soon as the single device leaves the middle position it is again under pressure which lasts until the machine performs one revolution and enters once more into the middle position.

Simultaneously with the entering into the middle position every device rides with the cam 56 of the elbow lever 49 upon a releasing roll 54 so that this lever is tilted and freed. The spring 50 brings the pressure-members until now locked back into their highest position. It is evident that the described movements are the same with every pressing device.

What I claim is:

1. In a vulcanizing press for applying soles to shoes, a rotatable carrier, a plurality of pressing and heating cushions on the carrier abutments for the shoes cooperating with the cushions, a fixed inlet of a heated pressure medium, a centrally arranged distributor connected to the inlet of the heated medium, and ducts in the distributor and in the rotatable carrier arranged to create a constant communication between the said inlet and the most of the cushions and to cut-off this communication between the said inlet and the rest of the cushions.

2. In a vulcanizing press for applying soles to shoes, a rotatable carrier, a plurality of pressing and heating cushions on the carrier abutments for the shoes cooperating with the cushions, a fixed inlet of a heated pressure medium, a centrally arranged distributor connected to the inlet of the heated medium, and ducts in the distributor and in the rotatable carrier arranged to create a constant communication between the said inlet and all the cushions but one and to cut-off this communication between the said inlet and the said one cushion.

3. In a vulcanizing press for applying soles to shoes, a rotatable carrier, a plurality of pressing and heating cushions on the carrier abutments for the shoes cooperating with the cushions, a fixed inlet of a heated pressure medium, a centrally arranged distributor connected to the inlet of the heated medium, ducts in the distributor and in the rotatable carrier arranged to create a constant communication between the said inlet and the most of the cushions and to cut-off this communication between the said inlet and the rest of the cushions, a safety valve allowing a part of the heated pressure medium to escape from the said communicating ducts, and exhaust ducts leading from a cushion cut-off from the source of the heated medium into the atmosphere.

4. In a vulcanizing press for applying soles to shoes, a rotatable carrier, a plurality of pressing and heating cushions on the carrier abutments for the shoes cooperating with the cushions, a fixed inlet of a heated pressure medium, a centrally arranged distributor connected to the inlet of the heated medium, and ducts in the distributor and in the rotatable carrier arranged to create a constant communication between the said inlet and all the cushions but one, to cut-off this communication between the said inlet and the said one cushion, exhaust ducts leading from the cut-off cushion into the atmosphere, and ducts in the distributor and in the rotatable carrier arranged to afford to the medium a free passage from a cushion communicating with the inlet of the medium through the cushion cut-off from the said source into the exhaust ducts.

5. In a vulcanizing press for applying soles to shoes, a rotatable carrier, a plurality of pressing and heating cushions arranged on the carrier inclined at an acute angle to the horizontal, and abutments for the shoes cooperating with the said cushions.

6. In a vulcanizing press for applying soles to shoes, a rotatable carrier, a plurality of pressing and heating cushions arranged on the carrier, every cushion consisting of a pan closed by a yielding cover and accommodated in second pan, the free space between both pans being filled with a heat insulating material, and abutments for the shoes cooperating with the said cushions.

HEINRICH WALTHER. 120
